OCCUPANT PROPELLED EXERCISING TOY
HORSE

James D. Jacobs, Wauseon, Ohio

Application November 1, 1949, Serial No. 124,800

3 Claims. (Cl. 280—1.196)

1

This invention relates to toys of the self propelled type and particularly of the type forming an exerciser and in particular this invention relates to a frame having a bolster or beam carried by four legs eccentrically mounted on wheels and over which a substantially hollow body or shell representing a horse or other animal may be placed whereby a rider moving upwardly and downwardly on the body with his feet in stirrups suspended therefrom and connected to the front 10 wheel mounting propels the device.

The purpose of this invention is to provide an exerciser in the form of a toy which not only provides amusement for both children and adults but also provides an exerciser that holds the 15 interest of a user thereof.

Various types of self propelled toys have been provided in the form of animals and also of different designs but these are usually actuated by pedals or other transmission elements and where they are provided in the form of a toy the only exercising value is in strengthening the legs of the user. With this thought in mind this invention contemplates an exerciser or toy wherein the motion of the body actuates the toy and provides propelling means therefor.

The object of this invention is, therefore, to provide a self propelled toy of the exercising type in which the toy is propelled by rocking movement of the body of an animal or the like thereon.

Another object of the invention is to provide an exercising toy that is adapted for use by both children and adults.

A further object of the invention is to provide an exercising toy which is of a simple and economical construction.

With these and other objects and advantages in view the invention embodies a freely mounted and removable body or shell positioned on a pivotally mounted beam with the beam carried by a frame mounted on wheels and with the wheels actuated by front and rear legs pivotally connected to the ends thereof and eccentrically connected to the wheels.

Other features and advantages of the invention will appear from the following description taken in connection with the drawings wherein:

Figure 1 is a side elevational view of the toy exerciser with the body of a horse positioned thereon.

Figure 2 is a plan view of the toy exerciser shown in Figure 1.

Figure 3 is a vertical longitudinal section through the device taken on line 3—3 of Figure 2.

Figure 4 is a sectional plan through the lower

5

part of the frame taken on line 4—4 of Figure 3.

Figure 5 is a cross section through the rear part of the device taken on line 5—5 of Figure 3.

Figure 6 is a similar section showing the front or forward end of the device and taken on line 6—6 of Figure 3.

Figure 7 is a detail showing the connection of the forward end of the beam to the front legs of the toy.

Figure 8 is a detail showing the connection of the stirrups of the toy to the vertical shaft or king pin in the forward end of the frame.

Referring now to the drawings wherein like reference characters denote corresponding parts the toy exerciser of this invention includes a rocking beam 10 pivotally mounted by a pin 11 on a frame 12 with the forward end of the beam connected to front wheels 13 and 14 by legs 15 and 16, respectively and with the opposite end connected to rear wheels 17 and 18 by rear legs 19 and 20, respectively and with the beam and upper part of the frame enclosed in a body or shell as indicated by the numeral 21.

The beam 10 is formed as illustrated in Figures 3, 5 and 6 and the forward end is provided with a tongue 22 to which the front legs 15 and 16 are pivotally connected by a pin 23 through a cross bar 24 and a brace 25, and the legs are pivotally connected to the cross bar by a pin 26. The lower ends of the legs 15 and 16 are eccentrically connected to the wheels 13 and 14 by pins 27 and 28, respectively, as illustrated in Figure 4. The wheels 13 and 14 are fixedly mounted on an axle 29 and the axle is journaled in bearings 30 and 31 of a yoke 32 at the forward end of a strut 33.

The forward end of the strut 33 and the yoke 32 are pivotally mounted on the lower end of a front shaft or king pin 34, the upper end of which is rotatably mounted in the forward end 35 of the frame 12 and the lower end of which is journaled in a bearing 36 at the lower end of a brace 37 extended downwardly from the frame 12, as shown in Figure 3. A bracket 38 is fixedly mounted on the king pin 34 by a clamp 39 and stirrups 40 and 41, suspended from the body 21 of the animal by a strap 42 are connected to the bracket 38 by arms 43 and 44, respectively. With the stirrups suspended by the strap 42 in this manner and substantially rigidly connected to the king pin 34 the king pin may readily be rotated by the stirrups to turn the yoke 32 for actuating the front wheels 13 and 14 for steering the toy.

The beam 10 is pivotally mounted on the frame

2

55

12 through a U-shaped yoke 45 that is pivotally attached to the beam by the pin 11 and secured to the frame 12 by a clamp 46, as shown in Figure 6.

The rear end of the beam 10 is pivotally connected to the legs 19 and 20 by a pin 47 extended through a bearing 48 on the under surface of the beam and the lower ends of the legs are eccentrically connected to the wheels 17 and 18 by pins 49 and 50, respectively.

The wheels 17 and 18 are fixedly mounted on a shaft 51 and the shaft is journaled in bearings 52 and 53 of a yoke 54 that is fixedly mounted on the lower end of the frame 12. The rear axle 51 and the yoke 54 are supported by an upwardly extended diagonal brace 55 and also by side braces 56 and 57.

With the parts arranged in this manner the animal is supported on the four wheels and the legs and body may be formed to represent a horse or animal or object as may be desired.

With a rider positioned on the body or shell 21 and with the feet in the stirrups 40 and 41 forward motion of the body starts the front wheels rotating forwardly or in a clockwise direction whereas the rear legs will draw the rear wheels upwardly to rotate the rear wheels also in a clockwise direction so that the animal will travel forwardly. As the forward end starts upwardly the rear will move downwardly and with this rocking motion continued by the body of the rider the animal will travel forwardly and at the same time the whole body will be exercised.

It will be understood that modifications may be made in the design and arrangement of the parts without departing from the spirit of the invention.

What is claimed is:

1. A toy exerciser comprising a frame, a rocking beam pivotally mounted intermediate of the ends thereof on the frame, wheels journaled in the frame for supporting the device, legs pivotally connected to the ends of the beam and eccentrically connected to the wheels, a body providing a cover for said beam and upper part of the frame, means pivotally mounting the wheels at the forward end of the frame in the frame, pedals suspended from the body, and means connecting the pedals to the wheels at the forward end of the body whereby the wheels may be turned by 50 the pedals for steering.

2. In an exerciser and toy, the combination which comprises a vertically positioned frame having a king pin in the forward end, a beam pivotally mounted intermediate of the ends thereof on the frame, supporting wheels rotatably mounted on the rear end of the frame, supporting wheels rotatably mounted on the lower end of the king pin in the forward end of the frame, legs pivotally mounted on the ends of the beam and eccentrically connected to the wheels, a body representing an animal positioned on the beam, and stirrups suspended from the body and connected to the king pin for actuating the wheels on the lower end of the king pin for steering.
3. In a toy exercising horse, the combination which comprises a frame having a horizontally disposed upper member with an arcuate rear end and having a depending bracket at the forward end, a rocking beam pivotally mounted intermediate of the ends thereof on the upper member of the frame, a vertically disposed king pin journaled in the forward end of the upper member of the frame and lower end of the bracket, a yoke on the lower end of the king pin, front wheels journaled in the yoke on the lower end of the king pin, rear wheels journaled on the lower end of the arcuate rear end of the frame, legs pivotally connected to the ends of the beam and eccentrically connected to the wheels, a body providing a cover for said beam and also for the upper part of the frame, a strut connecting the lower part of the arcuate rear end of the frame to the yoke at the lower end of the king pin, stirrups suspended from the body of the horse, and means connecting the stirrups to the king pin for actuating the front wheels for steering.
